UNITED STATES PATENT OFFICE.

JAY WILL LYSONS, OF NEW YORK, N. Y., ASSIGNOR TO JIFFY CORPORATION, OF NEW YORK, N. Y., A CORPORATION OF DELAWARE.

DESIGN FOR A SHAVING-BRUSH ATTACHMENT FOR TUBES CONTAINING CREAM.

Application filed August 21, 1928. Serial No. 27,904. Term of patent 3½ years.

To all whom it may concern:

Be it known that I, JAY WILL LYSONS, a citizen of the United States, residing at New York city, in the county of New York and State of New York, have invented a new, original, and ornamental Design for Shaving-Brush Attachment for Tubes Containing Cream, of which the following is a specification, reference being had to the accompanying drawing, forming part thereof.

The figure is a side elevation of my shaving brush attachment for tubes containing cream attached to a tube of cream shown in the dotted lines, showing my new design.

I claim:

The ornamental design for a shaving brush attachment for tubes containing cream as shown and described.

J. WILL LYSONS.
